UNITED STATES PATENT OFFICE.

GUY T. FOSTER, OF DAYTON, OHIO, ASSIGNOR TO LOCOMOTIVE ECONOMIZER CORPORATION, OF NEW YORK, N. Y., A CORPORATION OF DELAWARE.

FEED-WATER HEATER.

Application filed January 31, 1922. Serial No. 533,055.

To all whom it may concern:

Be it known that I, GUY T. FOSTER, residing at Dayton, in the county of Montgomery and State of Ohio, a citizen of the United States, have invented or discovered certain new and useful Improvements in Feed-Water Heaters, of which improvements the following is a specification.

My invention relates to feed water heaters and consists in improvements upon such a structure as is shown and described in Letters Patent of the United States No. 1,331,845, granted on my application February 24, 1920. The objects of my improvements are increased efficiency and fuller adaptation to service conditions.

The invention is illustrated in the accompanying drawings. Fig. I is a view in side elevation of the anterior portion of the boiler of a locomotive engine. In this illustration the front end of the boiler is truncated and the casing is broken away to show in elevation the heater within the smoke box. Fig. II is a view in front elevation of the assembly shown in Fig. I. Fig. III is a fragmentary view to larger scale, corresponding to Fig. II, but showing the structure in greater detail. Fig. IV is a fragmentary view in cross section, showing the rack for the tubes in position in the smoke box. Fig. V is a view in vertical section through one of the headers of the heater detached from its location in the locomotive, and showing in elevation the circulation tubes. The outward extending ends of these tubes are, however, broken away. Fig. VI is a view in side elevation, and Fig. VII a view partly in end elevation, partly in transverse vertical section of the same structure as that illustrated in Fig. V. The plane of section of Fig. V is indicated by the line V—V, Fig. VII, and the plane of section of Fig. VII is indicated by the line VII—VII, Fig. V. Fig. VIII is a view to still larger scale in longitudinal and medial section of one of the circulation pipes secured in the header walls.

I would preface further description with the remark that I show the heater of my invention in application to a locomotive engine, because that is the application in which I have developed it; but it will be understood that in so doing I do not limit the invention to use on locomotives. It is a

preheater for steam boilers and is applicable to steam boilers generally.

This preheater, or feed water heater (both terms are in use) is arranged in the smoke-box 1 of a locomotive 2. It extends from the anterior end of the smoke-box rearward toward the boiler proper. It is a two-part structure, arranged half on either side of the mid-line of the smoke-box, and in its rearward extent it lies on either side of the draft of steam from the exhaust 3 to the pipe 4 leading to the smokestack 5. As will be observed (Fig. II) the heater extends vertically from a level lower than the steam exhaust to a level higher than the lower end of pipe 4.

The two-part heater is bi-laterally symmetrical, and it will suffice to describe particularly one part. Each part consists of a header 6, arranged at the anterior end of the smoke box and circulation pipes 7 (a bank of pipes to each header) communicating with the headers, extending rearwardly from the headers, and accessible to the penetration of hot gases between and around the pipes.

Comparing Figs. I and II, it will suffice to remark (the arrangement is of the essence of the invention of my earlier patent referred to) that the flow of hot gases is forward from the boiler flues in divided stream on each side of the smoke box through the two banks of tubes then toward the mid-line of the smoke box, where the two streams unite. The united stream flows first rearward and then coming in the line of the steam exhaust it is carried upward and out through the smokestack.

The first feature of invention has to do with the mounting of the heater in the smoke box. A sill 19 is provided, and to it the header along its lower edge is secured. This sill plate at its outer end, the end, that is, which in assembly comes adjacent the smoke-box wall, is so formed as to constitute a foot, as by the lug 20; at the opposite end the sill extends beyond the edge of the header and is by such extension adapted to be secured, as by a bolt hole for an anchoring bolt. The header above is provided with an outstanding bracket 21 through which attachment to the smoke-box wall may be effected, as by bolting. On the inner wall of the smoke box a seat is formed for

the sill 19, as by the block 22 and post 23. The structure possesses these features: First, surfaces of block 22 and post 23 are surfaces upon which the header may be 5 slid to place; second, the overlapping lugs of sill 9 and block 22 afford a union such that the sill may be secured by a single bolt or single line of bolts 24 (cf. Fig. I); third, the bolts 24 (or equivalent securing means) 10 placed as they are beyond the edge of the header and toward the mid-line of the smoke box, are easily accessible for assembly and removal; fourth, the whole header structure is secured at three points, and by at the most 15 two bolts or two lines of bolts; fifth, the bolt holes for securing the sill to the header may be made oversize, and the overlapping lugs of sill 19 and block 22 may be arranged with clearance (see Fig. III) to the end that 20 thermal expansion and contraction may be free longitudinally of the sill from the anchorage 24.

The otherwise free ends of the circulation pipes rest in racks 10, and these racks are 25 provided with shoes 25. A bracket 26 (one or more, as may be required) is properly arranged within the smoke box, and on this bracket or brackets the shoes 25 slide until rack 10 attains desired position. 30 Slotted pins 27 with locking wedges 28 secure the rack in place on the bracket. This mode of mounting and securing makes possible assembly and removal with greatest facility and expedition.

35 The heater unit including header and circulation tubes may be assembled with sill and with rack and the whole introduced into and removed from the smoke box as circumstances may require. The securing devices are as has been said simple and accessible.

In the structure of my prior patent already alluded to the header is subdivided 40 interiorly into anterior and posterior chambers, and the circulation of water is from anterior chamber through tube and to posterior chamber. I now additionally provide for the repeated flow of the water through a succession of tubes. This I accomplish by 45 subdividing the anterior and posterior chambers of the earlier patent and forming a plurality of pairs of chambers in each header bringing the intake chamber of each succeeding pair into communication with the 50 outflow chamber of the preceding pair. Referring to Figs. V and VII, not only is the space within the header divided by the transverse and vertical wall 12 into anterior and posterior chambers, but it is further 55 subdivided by horizontal partitions 29 into a succession of pairs of anterior and posterior chambers. And, with Fig. V particularly in view, in which the right-hand side is the anterior side, and with the 60 understanding that the intake is to the flues, both inner and outer pipes were re- 65

lowermost anterior chamber and the outflow from the uppermost posterior chamber, it will be seen that the lowermost posterior chamber communicates directly through port 30 with the anterior chamber 70 of the next higher pair, and so on until the uppermost posterior chamber is reached, whence there is direct escape to the boiler. The number of these transverse partitions may be increased indefinitely; it will be 75 understood that with every such partition the same volumes of water are caused to circulate another time through the heating region. I find it convenient still further to subdivide the space within the header by 80 a vertical and longitudinal web 31.

Fig. VIII shows certain refinements of structure concerning the setting of the circulation tubes in the headers. The tubes are of the Field type explained in my prior 85 patent; they are formed of concentrically arranged pipes of larger and smaller diameter, the outer closed and the inner open-ended. The circulation is out from the header through the inner pipe, and back 90 through the space between the pipes. Accordingly, the outer pipe is set in the posterior wall of the header, and the inner in the partition wall 12.

A stock 32 with a conical threaded base 95 is seated in the anterior wall of the header, which in Fig. VIII bears the reference numeral 6. This stock spans the anterior chamber and its posterior end forms a plug 33 which comes snugly to place in an opening in the partition wall 12. The stock is hollow, there is communication from the anterior chamber of the header through lateral openings into the hollow space within, and the hollow opens longitudinally through 100 the plug 33 which as already explained comes to position in an opening in partition wall 12. Into this longitudinal opening in the posterior end of the stock the inner pipe 34 of the Field tube is threaded. A jamb 110 nut 35 secures the assembly. The posterior end of pipe 34 is slit and tongues 36 are bent aside, to serve as centering means for the free end of the inner pipe within the outer. The outer pipe is as before screw-threaded or expanded or welded into the posterior wall of the header. It is in virtue of the fact that the front wall of the header and the partition wall 12 are provided with openings for the reception of 115 stock 32 that before introduction of the stock the outer pipe 7 when brought to place is through the said openings accessible and its inner end may thus be reached and expanded or swedged to place in the posterior 120 wall of the header.

According to the specification of my earlier patent, the Field tubes of the heater being placed in alignment with the boiler 125

movable rearwardly through the boiler flues; according to the present arrangement, stock 32 with the inner pipe which it carries are removable as a unit through the anterior 5 wall of the header, and to this end the stock 32 is provided exteriorly with a block 37 which affords a wrench seat.

The mode of assembly is believed to be sufficiently explained in the foregoing 10 description.

The course of flow may be briefly indicated. Incoming water from the tank or other source of supply gains access to the lowermost anterior chamber of the header 15 through intake connection 13, and outflowing water passes from the uppermost posterior chamber to the boiler through outlet connection 14. Below-off nipples for anterior and posterior chambers are indicated 20 at 38 and 39.

I claim as my invention:

1. A feed-water heater equipment for a locomotive engine including in combination with a horizontally disposed cylindrical 25 smoke-box, a smokestack rising vertically from said smoke-box at a point intermediate the length of the smoke-box, and a steam exhaust directed vertically upward diametrically through the smoke-box and into 30 the smokestack, of twin heater halves provided with sill-plates, seats for said heater halves formed within the smoke-box, each seat including an inwardly opening horizontal slot arranged on either side adjacent 35 the smoke-box wall and adapted to receive the sill-plates of the heater halves when

thrust laterally in outward direction away from the medial vertical plane of the smoke-box, and means arranged adjacent the medial vertical plane of the smoke-box for 40 securing to place said heater halves when so thrust outward.

2. A feed-water heater equipment for a locomotive engine including in combination with a horizontally disposed cylindrical 45 smoke-box, a smokestack rising vertically from said smoke-box at a point intermediate the length of the smoke-box, and a steam exhaust directed vertically upward diametrically through the smoke-box and into 50 the smokestack, of twin heater halves each consisting of an anterior header provided with a sill-plate and of rearwardly extending circulation pipes, and means within the smoke-box for receiving and sustaining 55 the heater halves in removable condition, such means including slotted blocks for the sill-plates of the headers arranged on either side adjacent the walls of the smoke-box, posts for supporting the sill-plates of the 60 headers adjacent the medial vertical plane through the smoke-box, and racks for the circulation pipes, and removable means for securing the sills of the headers to said posts. 65

In testimony whereof I have hereunto set my hand.

GUY T. FOSTER.
